WORK FEEDING MECHANISM FOR SEWING MACHINES

Robert A. Hayes, Franklin Park, Ill., assignor to
 Union Special Machine Company, Chicago, Ill.,
 a corporation of Illinois

Application December 19, 1951, Serial No. 262,407

8 Claims. (Cl. 112—209)

1

This invention relates to sewing machines and, more particularly, to work-feeding mechanisms therefor. It has special reference to work-feeding mechanisms embodying a plurality of four-motion feed dogs having a differential action in relation to each other.

In the performance of various seaming operations, as in the seaming of rather easily stretchable fabrics, it has been recognized as desirable to employ a plurality of feed dogs, i. e., a main feed dog and an auxiliary feed dog, in tandem relation, these being arranged to impart different extents of feed to the work in advance of and to the rear of the point of stitch formation. Provision is frequently made for the adjustment of the relative movement of the feed dogs so arranged in tandem.

A primary object of the present invention is the provision in a sewing machine of means for simultaneously varying the feed stroke of a plurality of differentially operable feed dogs at the will of the operator while the machine is in operation. The arrangement contemplated is such that the change in feed stroke is accomplished without varying the ratio of the feed strokes of the several feed dogs so that the ratio determined as best suited for the particular work being performed is not disturbed.

Various purposes are served by this simultaneous change of the stroke of a plurality of feed dogs without interruption of the operation of the machine and without varying the relationship of the feeding actions of the feed dogs. By way of example, it permits the firm attachment of the end of an elastic strip across which a seam is being formed. Thus, if a seam is being formed across a relatively narrow elastic strip which would normally provide only four or five stitches across the strip, the action of a plurality of feed dogs may be varied simultaneously in passing across the strip, without interrupting the operation of the machine, to provide twenty or more stitches across the strip to firmly anchor the same. So also, an effect similar to a tacking operation may be performed at the beginning or end of a seam, or both, by greatly shortening the stitch length at the commencement or completion of a seam, or both, by the simple operation of a foot treadle or the like at the appropriate times.

A further object of the invention has been to provide means for readily changing the relative feed strokes of a plurality of feed dogs, controllable in the foregoing manner, so that the machine may be quickly adapted for most advantageous performance of various seaming operations upon materials of different character.

5

Thus, regardless of the preferred ratio of the feeding action of a plurality of feed dogs arranged in tandem, the length of the stitch produced may be instantaneously brought about, at the will of the operator, while the machine is in operation.

10

Other objects, features and advantages of the invention will appear from the detailed description of an illustrative form of the invention which will now be given in relation to the accompanying drawings, in which:

15

Figure 1 is a side elevational view of an over-edge sewing machine having the stitch-shortening mechanism of this invention incorporated therein, a portion of the machine being shown in section and parts of the machine being omitted and other parts being broken away for better illustration of still other parts;

20

Figure 2 is a front elevational view of the machine shown in Figure 1;

25

Figure 3 is a view partly in plan and partly in section, illustrating parts beneath the work support of the machine, the looper and parts of operating devices being omitted for clearer illustration of other parts;

30

Figure 4 is a perspective view illustrating the stitch-shortening mechanism and associated devices; and

35

Figure 5 is a perspective view of the variable driving connection for the feed rocker.

40

Referring now to the drawings wherein like reference numerals denote corresponding parts throughout the several views, I have illustrated therein an overedge sewing machine 10 in which the invention is incorporated. The machine includes a frame comprising a base or support bed 11, a standard 12 and a needle head 13 that overhangs a work support plate 14 carried by the base. A rotary drive shaft 15 is supported in the frame at an inclined acute angle with respect to the work support. One end of the drive shaft extends beyond the frame and is secured to a belt wheel 16 that is adapted to be connected to a suitable drive, such as an electric motor (not shown), for imparting rotation to the shaft. The other end of the shaft terminates in needle head 13 and is connected to an arrangement of devices 17 within the needle head for translating rotary movement of the shaft into reciprocatory movement of a needle bar 18. A needle 20 is secured to the lower end of the needle bar. Directly above work support 14 is a presser foot 21 that is normally urged in the direction of the work support by a spring-loaded presser bar 22 slidable in the needle head and extending therebelow.

45

50

55

55

The drive shaft carries a plurality of spaced

eccentrics, namely, eccentrics 23, 24, 25 and 26. It is to be borne in mind that a one-piece crank shaft may be used in lieu of straight shaft 15 and the eccentrics carried thereby. Eccentrics 23, 24, 25 and 26 are engaged by the upper strap members of corresponding pitman connectors 27, 28, 29 and 30, respectively. A reservoir 31 in the upper portion of the frame is adapted to contain a supply of lubricant, such as a suitable oil 32, which is delivered to the connections formed by the eccentrics and corresponding pitman straps by tubular devices 33 that contain wicking 34.

A trimming blade 35, for trimming a piece of work that is stitched by the machine in advance of the point of entry of needle 20 in the work, is attached to one end of a lever 36. This lever is pivoted at its other end to the frame, as indicated at 37, and is connected intermediate its ends to the lower strap of pitman 27.

An underlooper 40 and an overlooper 41 (Figure 1) cooperate with needle 20 in the formation of stitches in the piece of work. Pitman 26 contacts with devices (not shown) to operate underlooper 40. Pitman 29, in turn, contacts with other devices, also not shown, to operate overedge looper 41.

The work to be stitched is fed to the stitch-forming devices by a feeding mechanism that will now be described. This mechanism includes a main feed dog 43 and an auxiliary feed dog 44, both of which are carried by a main feed bar that is generally indicated by numeral 45 (Figures 3 and 4). The main feed bar comprises an arm 46 that is attached at one end to a feed rocker 47 which is rockable about a shaft 48 that is carried in a lug 49 integral with the base of the machine. Attached to the other end of arm 46 is a first block 50. A second block 51 is supported in spaced relation to block 50 by a plate 52 which is fastened to block 50 by screws 53 and to block 51 by screws 54 (Figure 3). Plate 52 has a slot 55. Block 51 carries a bracket 56 to which main feed dog 43 is attached by a screw 57.

Blocks 50 and 51 are provided with aligned bearing sleeves 60 and 61, respectively, which support a reciprocable cylindrical rod 62. Auxiliary feed dog 44 is affixed by a screw 63 to an extension 64 of rod 62. Thus, it will be observed that rod 62 constitutes the feed bar for auxiliary feed dog 44. Mounted on rod 62, intermediate blocks 50 and 51, is an additional block 65 which has a pair of set screws 66. These screws permit of ready adjustment of block 65 along the auxiliary feed bar. An arm 67 projects beyond one side of block 65 and registers with slot 55. This arrangement permits longitudinal movement of rod 62 and auxiliary feed dog 44, but prevents angular movement of these parts about the axis of rod 62. Attached to and extending beyond the opposite side of block 65 is a pin 68 that is pivotally connected to a driving link 69 for actuating rod 62 and, therefore, auxiliary feed dog 44. Link 69 carries a stud bolt 70 that extends through an arcuate slot 71 in a bracket 72 which is attached to feed rocker 47 by screws 73. A nut 74 secures a washer 75 to stud bolt 70. Washer 75 has a bent over extension 75' that projects into slot 71 and serves to prevent rotation of the stud bolt.

As is best shown in Figure 5, feed rocker 47 has a forwardly projecting arm 76 that is pivotally connected to the lower end of a link 77 by a bolt 78. This link has a forked upper portion 80 for the reception of an arm 61 of a rock bracket 82. Arm 81 has an arcuate slot 83 through which a bolt 84 carried by forked link portion 80 is adapted to pass. Bracket 82 is rockable about a shaft 85 that is supported in a machine base lug 86 (Figure 3) and is restrained against movement to the left along the shaft, as viewed in Figure 5, by a collar 87 that is affixed to the shaft by set screws 88.

Rock bracket 82 has an integral extension 90 that is spaced from the body thereof and defines a slot 91 therewith. A pin 92, threaded at its inner end, extends through extension 90 and is secured thereto by a nut 93 which is disposed in slot 91. Pin 92 carries a ball connector 94 that is engaged by a strap 95 at the lower end of pitman 30 (Figure 1). This pitman, by virtue of its interconnection with eccentric 26 and ball connector 94, imparts rocking movement to bracket 82 about shaft 85 in response to rotation of drive shaft 15. Also, inasmuch as feed rocker 47 is coupled to bracket 82 by arm 76 and link 77, the feed rocker is rocked simultaneously with bracket 82 upon rotation of the drive shaft.

Referring to Figures 1 and 3, pitman 27 carries a crank 96 at its lower end. This crank is pivotally connected by a link 97 to an arm 98 that is secured to block 51. Eccentric 23, pitman 27, crank 96, link 97 and arm 98 constitute connections for imparting lifting and lowering movements to main feed bar 45 and therefore to both feed dogs 43 and 44 in response to rotation of drive shaft 15.

Earlier described parts, including eccentric 26, pitman 30, ball connector 94, rock bracket 82, operating member 77, feed rocker 47, arm 46 and associated devices constitute cooperating connections for imparting feed and return movements to feed dogs 43 and 44 in response to rotation of the drive shaft. Thus, rotation of the drive shaft simultaneously imparts lifting and lowering movements and feed and return movements to the feed dogs.

The invention includes an arrangement of devices for shifting bolt 84 to the left as viewed in Figures 4 and 5, along slot 83, whereby to correspondingly tilt member 77 about the axis of bolt 78 and decrease the movement of feed rocker 47 and thereby shorten the length of stitches formed by the stitch-forming devices at will during the operation of the machine. These devices comprise a linkage, including a link 100 that is engaged at one end by bolt 84 and is clamped thereby to forked portion 80 of member 77. Link 100 is pivoted at its other end, as indicated at 101, to an arm 102. This arm is secured to and rockable with a shaft 103 that is rotatably supported in a lug 104 carried by the machine base. Another arm 105 engages a threaded extension 106 of shaft 103 and is affixed thereto by nuts 107. Arm 105, as in the case of arm 102, is rockable with shaft 103 and is pivoted at 108 to an upstanding link 109. Link 109 has a pivot pin 110 that is connected to an end of an arm 111 that is secured to the inner end of a shaft 112 which is mounted for rotation in a machine base lug 113 (Figure 3). Mounted on the inner end of shaft 112 is a coil spring 114. One end of the spring engages arm 111 and the other end bears against the machine frame in a manner to normally and yieldingly urge arm 111 and shaft 112 in a counter-clockwise direction, as viewed in Figure 4. An operating lever 115 is secured to the outer end of shaft 112 through the medium of a threaded shaft extension 116 and a pair of nuts 117. This lever is

connected to a depending chain 118 that is adapted to be attached to a knee press pad or foot treadle (not shown). A bracket 120 is affixed to the machine base by a screw 121. This bracket has a vertical slot 122. A pair of spaced stop pins 123 and 124 register with slot 122 and are vertically adjustable as allowed by the extremities of the slot.

For the purpose of briefly outlining the operation of the machine, it is first assumed that the parts are assembled and are in the relative position shown in the drawings. With the parts in such position, operating lever 115, due to the action of spring 114, is in its normal position, i. e., it bears against upper stop pin 123 (Figure 4). Also, bolt 84 is disposed in the righthand end of slot 83 due to the connection of this bolt with lever 115 through the intermediary of link 100, arm 102, shaft 103, arm 105, link 109, arm 111 and shaft 112. As a consequence, member 77 is so positioned that the feed dogs operate in a manner that the stitch-forming devices will make the longest stitches for which the machine is set.

When the machine is placed in service, rotation of drive shaft 15 and eccentrics 23 and 26 actuates pitmans 27 and 30 to simultaneously impart lifting and lowering movements and feed and return movements to the feed dogs 43 and 44. While both feed dogs are carried by arm 46 and associated devices and are subject to the action of feed rocker 47, they are so arranged as to result in a differential feed action in relation to each other.

At such times as it may be desirable to shorten the stitch lengths, the operator, while the machine is in service, merely actuates the knee press pad or foot treadle, as the case may be, thereby pulling downwardly on chain 118. This causes lever 115 to swing downwardly and shaft 112 to move in a clockwise direction, as viewed in Figure 1, thereby raising arm 111 and actuating link 109, arm 105, shaft 103, arm 102 and link 100 in a manner to shift bolt 84 toward the left along slot 83. This correspondingly swings member 77 toward the left, as viewed in Figures 1 and 5. This decreases the extent of movement of feed rocker 47 and as a consequence shortens the feed of both feed dogs and the length of stitches formed by the stitch-forming devices. The parts are so arranged and connected that the differential ratio between the feed dogs is constant regardless of the length of stitches formed by the machine.

Thus it will be seen that the construction herein shown and described is well adapted to accomplish the objects of the present invention. It will be understood, however, that the invention may be embodied otherwise than as herein shown, and that in the form illustrated certain obvious changes in construction may be made. Therefore, I do not wish to be limited precisely to the construction herein shown except as may be required by the appended claims considered with reference to the prior art.

I claim:

1. In a sewing machine having a rotary drive shaft and stitch-forming devices driven therefrom, the combination of work-feeding means comprising a plurality of feed dogs, first connections from said shaft for simultaneously imparting lifting and lowering movements to said feed dogs, second connections from said shaft for imparting feed and return movements to said feed dogs, a feed rocker common to said first and second connections, said second connections including a device rockable in response to rotation

of said shaft, said feed rocker and device being rockable about different axes, and means connecting said device with said feed rocker and separately connecting said feed rocker with each of said feed dogs, said connecting means enabling different feed and return movements to be imparted to the several feed dogs, and means interposed in the connections between said shafts and said feed rocker operable at will during the operation of the machine for varying the extent of movement of said feed rocker.

2. In a sewing machine having a rotary drive shaft and stitch-forming devices driven therefrom, the combination of work-feeding means comprising a plurality of feed dogs, first connections from said shaft for simultaneously imparting lifting and lowering movements to said feed dogs, second connections from said shaft for imparting feed and return movements to said feed dogs, a feed rocker common to said first and second connections, said second connections including a device rockable in response to rotation of said shaft, said feed rocker and devices being rockable about different axes, and means connecting said feed rocker with each of said feed dogs, said connecting means enabling different feed and return movements to be imparted to the several feed dogs, means in said connecting means for varying the relative extent of movement of the several feed dogs, and means interposed in the connections between said shaft and said feed rocker operable at will during the operation of the machine for varying the extent of movement of said feed rocker.

3. In a sewing machine having a rotary drive shaft and stitch-forming devices driven therefrom, the combination of work-feeding means comprising a plurality of feed dogs, first means connected to and operable in response to rotation of said shaft for imparting lifting and lowering movements to said feed dogs, second means connected to and operable in response to rotation of said shaft for imparting feed and return movements to said feed dogs, said second means including a feed rocker and a rocker bracket that are rockable about different axes, a link connecting said feed rocker with said rocker bracket, and connections separately connecting said feed rocker with each of said feed dogs, said connections enabling different feed and return movements to be imparted to the several feed dogs, and means interposed between said feed rocker and said rocker bracket operable at will during the operation of the machine for varying the extent of movement of said feed rocker.

4. In a sewing machine having a rotary drive shaft and stitch-forming devices driven therefrom, the combination of work-feeding means comprising a plurality of feed dogs, first means including a feed rocker connected to and operable in response to rotation of said shaft for imparting lifting and lowering movements to said feed dogs, second means connected to and operable in response to rotation of said shaft for imparting feed and return movements to said feed dogs, said second means including said feed rocker and a rocker bracket that are rockable about different axes, and connections separately connecting said feed rocker with each of said feed dogs, said connections enabling different feed and return movements to be imparted to the several feed dogs, and means comprising a linkage interposed between said feed rocker and said rocker bracket operable at will during the opera-

tion of the machine for varying the extent of movement of said feed rocker.

5. In a sewing machine having a rotary drive shaft and stitch-forming devices driven therefrom, the combination of work-feeding means comprising a plurality of feed dogs, first means including a feed rocker connected to and operable in response to rotation of said shaft for imparting lifting and lowering movements to said feed dogs, second means connected to and operable in response to rotation of said shaft for imparting feed and return movements to said feed dogs, said second means including said feed rocker and a rocker bracket that are rockable about different axes, and connections separately connecting said feed rocker with each of said feed dogs, said connections enabling different feed and return movements to be imparted to the several feed dogs, and means interposed between said feed rocker and said rocker bracket operable at will during the operation of the machine for varying the extent of movement of said feed rocker, said last named means comprising a link having one end pivotally connected to said feed rocker and its other end shiftably connected to said rocker bracket.

6. In a sewing machine having a rotary drive shaft and stitch-forming devices driven therefrom, the combination of work-feeding means comprising a plurality of feed dogs, first means including a feed rocker connected to and operable in response to rotation of said shaft for imparting lifting and lowering movements to said feed dogs, second means connected to and operable in response to rotation of said shaft for imparting feed and return movements to said feed dogs, said second means including said feed rocker and a rocker bracket that are rockable about different axes, and connections separately connecting said feed rocker with each of said feed dogs, said connections enabling different feed and return movements to be imparted to the several feed dogs, a link having one end pivotally connected to said feed rocker and its other end shiftably connected to said rocker bracket, and a linkage coupled to said link and operable at will during the operation of the machine for shifting said other end of said link relative to said rocker bracket to correspondingly vary the extent of movement of said feed rocker.

7. In a sewing machine having a rotary drive shaft and stitch-forming devices driven therefrom, the combination of work-feeding means comprising a plurality of feed dogs, first means

including a feed rocker connected to and operable in response to rotation of said shaft for imparting lifting and lowering movements to said feed dogs, second means connected to and operable in response to rotation of said shaft for imparting feed and return movements to said feed dogs, said second means including said feed rocker and a bracket member that are rockable about different axes, a link member pivotally connected at one end to said feed rocker, one of said members having a slot formed therein, the other of said members being coupled to and shiftable along said slot in said one of said members, and connections separately connecting said feed rocker with each of said feed dogs, said connections enabling different feed and return movements to be imparted to the several feed dogs, and means secured to said link member and operable at will during the operation of the machine for shifting said link member relative to said bracket member to correspondingly vary the extent of movement of said feed rocker.

8. In a sewing machine having a rotary drive shaft and stitch-forming devices driven therefrom, the combination of work-feeding means comprising a plurality of feed dogs, first means including a feed rocker connected to and operable in response to rotation of said shaft for imparting lifting and lowering movements to said feed dogs, second means connected to and operable in response to rotation of said shaft for imparting feed and return movements to said feed dogs, said second means including said feed rocker and a feed bracket that are rockable about different axes, said feed bracket having a slot formed therein, a link having one end pivotally connected to the feed rocker and its other end coupled to and shiftable along said slot in said feed bracket, and connections separately connecting said feed rocker with each of said feed dogs, said connections enabling different feed and return movements to be imparted to the several feed dogs, and means comprising a linkage connected to said link and operable at will during the operation of the machine for shifting said other end of said link along said slot to correspondingly vary the extent of movement of said feed rocker
